UNITED STATES PATENT OFFICE.

ALFRED SPANGENBERG, OF PLAINFIELD, NEW JERSEY, ASSIGNOR TO
NILES-BEMENT-POND COMPANY, OF JERSEY CITY, NEW JERSEY.

RATCHET MECHANISM.

SPECIFICATION forming part of Letters Patent No. 764,311, dated July 5, 1904.

Application filed April 4, 1904. Serial No. 201,492. (No model.)

To all whom it may concern.

Be it known that I, ALFRED SPANGENBERG, a citizen of the United States, residing at Plainfield, Union county, New Jersey, (post-office address, No. 826 West Sixth street, Plainfield, New Jersey,) have invented certain new and useful Improvements in Ratchet Mechanism, of which the following is a specification.

There is a class of ratchet mechanism employed in transmitting rotary motion from a driver to a driven member where the driver makes an indefinite number of turns in alternating direction and in which the driven member is to make a definite number of turns. Such devices are often used on metal-planing machines where the driver is represented by an element turning in alternative directions and to a varying extent dependent on the length of table-stroke being immediately dealt with and in which the driven member is a feed part moved a definite degree at each table-stroke.

My present invention embodies very substantial improvements upon known devices of very much similar general construction.

My present invention will be readily understood from the following description, taken in connection with the accompanying drawings, in which—

Figure 1 is a front elevation of a ratchet mechanism employing my present improvements; Fig. 2, a substantially horizontal section of the same in the plane of line *a* viewed from below, and Fig. 3 a vertical section in the plane of line *b* viewed from the front.

In the drawings, 1 indicates a fixed housing illustrated as in mere plate form, which housing may well serve as the back for a casting to contain the mechanism, its outline being immaterial, the rectangular form being illustrated, mainly, for the purpose of suggesting to the eye the non-rotary character of this part; 2, a hollow shaft journaled in the housing and constituting the driven member of the mechanism; 3, a disk fast on this shaft; 4, a double-ended pivot-pawl carried by this disk; 5, a brake engaging the disk and serving to prevent erratic movements of the disk under certain conditions, this brake not being needed in all cases; 6, a shaft concentrically mounted

in the hollow shaft 2 and forming the driver of the system; 7, a ratchet fast on this driving-shaft and having its teeth facing in both directions appropriate to coöperation with the opposite ends of the pawl alternatively; 8, a clutch-ring frictionally carried by the ratchet, this ring being illustrated as a gap-ring spring-expanded with a facial recess in the ratchet; 9, an arm projecting inwardly from the pawl and carrying a pin engaging the clutch-ring in such manner that if the clutch-ring shift angularly relative to the pawl it will rock the pawl; 10, a pair of fixed cams in the path of the pawl and adapted when engaged by the pawl to tip the pawl out of engagement with the ratchet, all of the parts thus far referred to being generally considered of usual construction and arrangement; 11, a pair of supercams pivoted on the fronts of fixed cams 10 and coöperating with the latter upon the pawl, these movable cams having faces projecting at points inwardly beyond the faces of the fixed cams; 12, a pin projecting from the rear face of each supercam into a substantially radial slot in the fixed cam to permit of but limit the movement of the supercams relative to the fixed cams; 13, a spring carried by each fixed cam and pressing inwardly upon the pin 12 to urge the supercam to normal inward position; 14, a spring for expanding the clutch-ring; 15, a fixed outward projection from the housing toward the back of pawl-carrying disk 3; 16, buffers or stops, preferably of fiber, dovetailed into the angular faces of the projection 15, and 17 a stop-lug carried by the back of pawl-carrying disk 3 in position to have its opposite angular faces coöperate alternately with the two buffers 16.

Driving-shaft 6, with its ratchet, is to make an indefinite number of turns, first in one direction and then in the other. Driven shaft 2 is to make a partial turn of constant extent, first in one direction and then the other. In short, as the driving-shaft 6 reverses its direction of motion the driven shaft 2 is to accompany it in its rotation through a definite portion of a turn and then come to rest.

In Fig. 3 the angular distance swept through

by stop-lug 17 on the disk 3 measures the definite degree of rotation of the driven shaft, the angular faces of the stop-lug striking first one and then the other buffer, the buffers serving 5 to effect a sufficiently definite arrest without involving an undesirable amount of noise or rebound.

In Fig. 1 assume the ratchet turning in the direction indicated by the arrow. It is driving the driven shaft in the same direction 10 through the medium of the pawl. Assume supercams 11 to be absent. In course of time the advance extremity of the pawl engages the right-hand one of fixed cams 10, with the result that the pawl is tipped out of engagement 15 with the ratchet, whereupon the driven shaft comes to rest, the driving-ratchet continuing on. This enforced tipping of the pawl is opposed by clutch-ring 8, whose tendency is to 20 urge the pawl again to the ratchet. If the rotary motion of the parts be slow, then the driven member will come to rest the instant the cam has disengaged the pawl from the ratchet-tooth with which it was engaged, and 25 the result may be that the pawl has not cleared the ratchet-tooth sufficiently to avoid such contact as will produce undesirable wear and noise. Furthermore, the time of release as 30 effected by the cam is subject to variations as the cam or the pawl or the teeth become worn, and at these slow speeds the release may take place before the driven member reaches its stop, and it is manifest that breakage will occur if the release takes place after the buffer 35 has been engaged. If the parts turn at high speed, then after the release of the pawl momentum may carry the driven parts to the buffer-point, but rebound therefrom may carry the pawl far enough back on the cam to cause 40 the pawl to make contact with the tips of the teeth. Such has been the unsatisfactory action of devices of this construction in the absence of the supercams.

Now in the present construction the supercams are held to working position by springs 45 strong enough to tip the idle pawl against the resistance of the clutch-ring 8, but not strong enough to release the pawl from working engagement with the ratchet-tooth. The result 50 is that the supercam becomes pushed outwardly, and the fixed cam does the work of releasing the pawl from the tooth, the actual release taking place at as sharply a defined point as may be and the supercam then moving 55 inwardly and completing the tipping of the pawl to the neutral position, quite out of danger of any possible contact with the teeth. This action may be relied upon no matter how slowly the parts turn. In the older arrangements 60 the brake 5 was required to do some-what heavy work, costing power and increasing the wear on all parts, as its resistance was requisite to insure proper action. In the present construction the brake need act but

lightly in any case and for slow motions is 65 not necessary at all, as supercams will keep the pawl from again engaging the ratchet.

The reversal takes place in an obvious manner, the first effect of the reversal of the direction of motion of the ratchet-wheel being 70 through the medium of the clutch-ring to tip the pawl from the neutral into appropriate engagement with the ratchet, whereupon the driven member accompanies the driver till the pawl is released by the second cam. In 75 the older constructions the clutch-ring was required to work rather tightly, as it was liable to have to deal with a pawl tipped only to the clearing angle, while in the present construction the supercams insure the tipping of the 80 pawl to the natural position, and the clutch-ring has a comparatively light duty to perform, the general result being a more positive working, a superior freedom from the lost work of friction, and a greatly increased 85 durability of the parts. In the older constructions much annoyance has been experienced from the wearing of the points of the teeth and pawl. Again, in the older constructions it was necessary that the pawl engage the 90 teeth at an easily-releasing angle of contact, while in the present construction the angle of the tooth-faces may be much more nearly radial.

I claim as my invention—

1. In a ratchet mechanism, the combination, substantially as set forth, of a rotary driver having a double-faced ratchet, a rotary driven member carrying a double-ended pivoted pawl, a friction device carried by the 100 driver and tending to tip the pawl in position to cause the driven member to turn with the driver, a pair of fixed cams in the path of the pawl to engage the pawl and tip it out of engagement with the ratchet, and a spring- 105 pressed supercam on each fixed cam adapted to tip the pawl to neutral position after the fixed cam has released it from the ratchet-wheel or while it is so releasing it.

2. In a ratchet mechanism, the combination, substantially as set forth, of a rotary driver having a double-faced ratchet, a rotary driven member carrying a double-ended pivoted pawl, a friction device carried by the 110 driver and tending to tip the pawl in position to cause the driven member to turn with the driver, a pair of fixed cams in the path of the pawl to engage the pawl and tip it out of engagement with the ratchet, a stop-lug carried by the driven member, a fixed stop presenting two angular faces in the path of said 115 stop-lug, and buffers dovetailed into the faces of the fixed stop.

ALFRED SPANGENBERG.
